UNITED STATES PATENT OFFICE.

ABIA Z. BODA, OF WASHINGTON, DISTRICT OF COLUMBIA, ASSIGNOR TO
CHRISTIAN DEVRIES, MINNIE A. VOGELER, AND HERMAN D. UMBSTAET-
TER, ALL OF BALTIMORE, MARYLAND.

DESIGN FOR A STATUE.

SPECIFICATION forming part of Design No. 14,809, dated February 26, 1884.

Application filed December 19, 1883. Term of patent 14 years.

To all whom it may concern:

Be it known that I, ABIA Z. BODA, a citizen of the United States, residing in Washington, in the District of Columbia, have invented and produced a new and original Design for a Statue, of which the following is a specification, reference being had to the accompanying photographs, forming part thereof.

10 The leading feature of my design is the representation or figure of a long-bearded man standing erect on a pedestal. The left arm is raised, and the hand, which is somewhat higher than the top of the head, holds a bottle-shaped device. The right hand is supported on the top of a cane that rests on the tablet above the cornice, about midway between the man's feet, which are wide apart. The figure of the man is arranged in a flowing gown, secured at 15 the waist with a cord and reaching to the feet, the gown having a hood, which is drawn over

the head, and loose sleeves, the left one of which has slipped to the elbow, leaving the forearm bare. The dado of the pedestal has on its face an oviform space formed by the 25 junction of raised curves, and intended to contain a suitable inscription, and the base of the pedestal is ornamented with scroll-work.

The photograph sufficiently represents the design without describing the back or sides. 30

I claim—

The design for a statue herein shown and described, the same consisting of the representation of the bearded and gowned man, with left arm raised, right hand resting on a cane, and standing on a pedestal, all as hereinbefore set forth.

ABIA Z. BODA.
